UNITED STATES PATENT OFFICE.

ARCHIBALD R. STEPHEN, OF LODI, CALIFORNIA.

ALMOND SEPARATOR.

Application filed August 30, 1920. Serial No. 406,904.

To all whom it may concern:

Be it known that I, ARCHIBALD R. STEPHEN, a citizen of the United States, residing at Lodi, county of San Joaquin, State 5 of California, have invented certain new and useful Improvements in Almond Separators; and I do declare the following to be a full, clear, and exact description of the same, reference being had to the accompanying drawings, and to the characters of reference marked thereon, which form a part of this application.

This invention relates to improvements in almond separating devices, and is particularly intended to be used in connection with my improved "almond huller," an application for patent which was filed November 22nd, 1919, Serial No. 340,027, and allowed June 15th, 1920.

20 The principal object of this invention is to provide a device by means of which the almonds received from the huller will be separated from the hulls intermingled therewith in such a manner that but a few if 25 any hulls will be left with the almonds discharged from the separator.

A second object is to provide a means for preventing any of the almonds or hulls from sticking in the screens, or rather for 30 releasing them when once so caught in the screen-mesh, and in such a manner that the almonds will not be damaged or chipped in the least.

A third object is to provide a blower arranged to direct a current of air across the discharge opening from the huller between said opening and the topmost screen, and into an enlarged pipe, carried to the outside of the building or any suitable distance away from the separator. This current of air acts against the almonds and hulls dropping from the huller, and while not powerful enough to force the same into the discharge pipe, carries away all the 45 leaves and the light hull-fluff and fuzz, which latter usually rise in the air around a separator and are breathed by the workers to their discomfort and to the detriment of their health. For this reason separator- 50 work is usually looked forward to with dislike and dread of possible injurious consequences.

With my improved device however, this obnoxious feature is eliminated.

55 A further object of the invention is to produce a simple and inexpensive device,

and yet one which will be exceedingly effective for the purposes for which it is designed.

These objects I accomplish by means of 60 such structure and relative arrangement of parts as will fully appear by a perusal of the following specification and claim.

In the drawings similar characters of reference indicate corresponding parts in the 65 several views.

Fig. 1 is a side elevation of my improved separator.

Fig. 2 is a half end elevation thereof.

Fig. 3 is a fragmentary detached view of 70 a screen-agitating means.

Fig. 4 is a fragmentary top plan view of the preferred form of screen used.

Fig. 5 is a top plan view of the screen-support brackets, showing the adjustability 75 thereof.

Fig. 6 is a fragmentary section taken on the line 6—6 of Fig. 1, showing the means for adjusting the brushes.

Referring now more particularly to the 80 characters of reference on the drawings, the numeral 1 denotes a suitable and vertical framework preferably rectangular, on top of which at one end and transversely thereof is a huller 2 of the type shown in the 85 aforementioned application.

The under side of this huller is enclosed with sheet-metal plates 3, the ones 3^a which extend longitudinally of the huller but transversely of the frame converging toward each other below the huller to form a discharge outlet 4.

Positioned just below the termination of the plate 3^a and extending lengthwise thereof is the outlet or nozzle 5 of a blower 6 95 mounted on the frame 1, there being a discharge pipe 7 opposite the nozzle 5 and beyond the huller-discharge opening 4, said pipe leading away from the separator to the outside of the building or any other suitable point.

Adjacent the outlet 4, this pipe is preferably rectangular, and has pivoted therein near the bottom a horizontal rod 8 having upstanding prongs 9, so spaced as to 105 prevent any almonds from passing therebetween. The rod 8 however is turnable so that the prongs may be moved to leave a free passage through the pipe 7 in the event that it is desired to allow hulls 110 to pass therethrough, these being lighter than the almonds, which, even if they were

blown along by the air-blast, would drop and hit the prongs adjacent the rod.

Below the huller-outlet and blower nozzle and discharge and extending lengthwise of the frame 1 is a stack of horizontal screens 10 spaced vertically a desired distance and connected together by a frame 10^a to form a rigid unit independent of the frame.

Each screen comprises a rectangular framework 11 and transverse and horizontally waved wires 12, those on the different frames being spaced apart decreasing distances from the topmost to the lowermost screen.

15 To keep the wires spaced in proper relation midway of the width of the frames, I provide vertical spacer-strips 13 extending lengthwise of the tray-frames, and through which the wires pass.

20 The screen-frame 10^a is mounted on hickory or some similar elastic supports 14, which are set at a longitudinal angle and fixed to longitudinally adjustable brackets 15 on the frame 1. The adjustment of these 25 brackets individually may be had by reason of longitudinal slots 15^a in the foot pads 15^b of the brackets, through which pass clamping bolts 15^c, embedded or fixed in the longitudinal beams 1^a of the frame 1.

30 To impart a longitudinal agitating movement of a jerky nature to the screens, I provide longitudinal beams 16, preferably of some elastic hardwood, fixed to the under side of the lowermost screen adjacent the 35 outer edges thereof and extending downwardly at an acute angle. Into the lower ends of these beams are fixed rods 17 which are adjustably connected to eccentric straps 18 turnably mounted on eccentric portions 40 19 formed on a transverse driven shaft 20 mounted to the frame 1, there being a fly wheel 20^a on this shaft to insure steady movement.

When this shaft is rotated at a proper 45 and fairly high speed, the screen structure is caused to be agitated back and forth and through a slight distance vertically, the extent of such movement being governed by adjusting the brackets 15 and the rods 17 50 relative to the straps 18.

Under the screen structure and extending lengthwise thereof between the beams 16 and supports 14 is an endless driven conveyor-belt 21, of canvas or other suitable material, 55 adapted to carry away the hulls dropping through the lowermost screen.

To insure the hulls dropping onto the conveyor, guide plates 22 are positioned under the lower screen to the frame 10^a and slant 60 inwardly toward the conveyor.

The majority of hulls however will not pass through to the lowest screen, but will be held on the upper ones, and will move toward that end of the screens farthest from 65 the huller by reason of the agitating of the

screens, to be deposited in a chute or trough 23 leading to any desired point.

The ends of the two succeeding screws below this are provided with a discharge chute 24 onto which the nuts fall after traversing the length of the screens, from which chute the nuts may be conveyed where desired.

To prevent any almonds or hulls from sticking between the wires of the screens, I 75 provide transverse brushes 25 under each screen, preferably having flexible steel bristles which project slightly between the screen-wires.

These brushes are all mounted for vertical adjustment to a common vertical framework 26 outside the screen frames but inside the main frames 1, the frame 26 having vertically spaced rollers 27 on each side running on horizontal tracks 28 fixed to the frame 1. 80 Individual adjustment of the brushes and at either end is obtained by means of the following structure: The frames 26 are either slotted vertically or each formed as a pair of transversely spaced and parallel bars, as 85 shown in Figs. 2 and 6. The back-bars or frames 25^a of the brushes extend over and rest against these frame members 26 and have clamping bolts 25^b passing between the 90 frames and then through washers 25^c bearing against the opposite edges of the members 26. In this manner, by loosening the bolts, the brush members may be raised or lowered at either end, or both, as may be desired.

100 There are two such brushes for each screen, each brush being arranged to move along one-half of the screen, so that a pair of brushes thus takes care of the entire screen-area. This movement is imparted to the 105 brush-frame as follows:—Journaled on the frame 1 in horizontal alinement on each side of the frame 26 and spaced apart lengthwise a distance equal to half the length of the screens are sprocket wheels 29, one of which 110 on each side is driven. An endless chain 30 passes over each pair of sprockets, and from one link thereof a flexible connection 31 extends to the frame 26 and is fixed thereto at a point on the line between the sprocket-centers. This frame is of course so positioned relative to its connection with the chain that with the movement of the chain from one sprocket to the other, the frame 26 will be similarly moved from one end of the 115 screen-frames to the half-way point thereon.

The connection 31 is preferably a coiled spring mounted on horizontal pins, so that it may be longer than the radius of the sprockets, so as to pull at an angle and at 120 the same time allow it to contract so as to permit it passing around the sprockets at the end of its travel in one direction without buckling.

In practice, I preferably connect the 130

huller-shaft 2^a direct to the power, and from this shaft run a belt drive 32 to the blower, a chain drive 33 to the shaft 20, and a chain drive 34 to one of each of the sprockets 29.

5 This arrangement may however be varied as may be found desirable or convenient.

In operation, the hulls and almonds drop from the huller onto the topmost screen while being subjected to the air-blast from 10 the blower, which carries away all leaves and light fluff and dust.

The topmost screen is preferably only half the length of the remainder, and this screen, together with the adjacent one underneath, 15 carry the large hulls over to the conveyor 23, the nuts and smaller hulls and parts dropping through onto the lower screens and onto the chute 24, the lowest screen having such narrow wire-spacing as to prevent any 20 nuts passing therethrough, but only the small pieces of hulls and the like.

At the same time, the brushes are constantly moving back and forth under the screens, immediately loosening any nuts or 25 hulls tending to stick between the wires, and on account of their flexibility, preventing the nuts from being damaged or the screen-wires from becoming bent out of proper alinement.

From the foregoing description it will 30 be readily seen that I have produced such a device as substantially fulfills the objects of the invention as set forth herein.

While this specification sets forth in detail the present and preferred construction 35 of the device, still in practice such deviations from such detail may be resorted to as do not form a departure from the spirit of the invention, as defined by the appended claim.

Having thus described my invention, what 40 I claim as new and useful and desire to secure by Letters Patent is:—

An almond separator including a fixed frame, horizontal screens disposed therein in vertically spaced alinement, an independent frame outside the screens, rollers on the latter frame, guide rails on the fixed frame on which the rollers rest, said independent frame being adapted for longitudinal movement relative to the screens, 45 brushes on said movable frame extending under all the screens, an endless flexible drive extending lengthwise of the movable frame and elastic means connected to the drive and the movable frame. 50 55

In testimony whereof I affix my signature.

ARCHIBALD R. STEPHEN.
